UNITED STATES PATENT OFFICE.

RICHARD FITZGERALD, OF CHICAGO, ILLINOIS.

DEVICE FOR ACTUATING FLUID-PRESSURE BRAKES.

SPECIFICATION forming part of Letters Patent No. 608,661, dated August 9, 1898.

Application filed July 28, 1897. Serial No. 646,204. (No model.)

To all whom it may concern:

Be it known that I, RICHARD FITZGERALD, residing in Chicago, Cook county, Illinois, have invented a certain new and useful Device for Actuating Fluid-Pressure Brakes, of which the following is a specification.

The object of my invention is to provide a valve device for automatic air-brakes of the quick-action type which shall be simple in construction and positive and reliable in operation.

In the accompanying drawings, Figure 1 is a sectional elevation of the valve device, showing the parts in their normal or running position. Fig. 2 is a similar view in service application of the brakes; Fig. 3, a similar view in emergency application, and Fig 4 an end view of the service-valve.

The portion 1 constitutes the casing proper of the device, and is provided with two chambers 2 and 3, formed in the casing and containing the operating parts of the device. The end of the casing is closed by a suitable cap or plate 4.

The outer portion of chamber 2 forms a cylinder, in which travels the release-valve piston 5, whose stem operates the slide-valve 6, movable upon the bushing 7 in the inner portion of such chamber. The usual by-port 8 is provided around the piston in order that the air may be fed into the auxiliary reservoir, into which the chamber 2 leads at 9.

The casing has a train-pipe connection 10, from which leads a supply-passage 11 through the cap or plate and into the chambers 2 and 3. The chamber 3 communicates with the auxiliary reservoir through passage 12, which is closed by a flap-valve 13 or other suitable means which prevents flow of air from chamber 3 into the reservoir. This valve may be dispensed with, but is preferably used to provide against any possible leakage of air through the parts of the device working in chamber 3. This chamber also communicates with the brake-cylinder by passage 14 and with the train-pipe through passage 15, which is controlled by any suitable check-valve 16. The chamber 3 contains the mechanism for setting the brakes, both in service and emergency application thereof. This mechanism comprises a main piston 17, a service-valve 18, and an emergency-valve 19.

The main piston is preferably in the form of a cylinder traveling in the chamber 3 and having a passage through its central portion. 55 This piston governs the passage 15, leading from the train-pipe into chamber 3. Within the central portion of the main piston is arranged the emergency-valve 19, normally seated upon a seat 20. The service-valve 18 is arranged within the emergency-valve and has its seat formed upon the latter valve, so that when the valves are in normal or running position the passage 14 is closed.

The inner face of the main piston is provided with a circular shoulder 21, which when this piston makes its full travel abuts against an annular ring 22 at or near the end of the emergency-valve.

The service-valve comprises a head and a stem, the head being retained, if desired, by a keeper-ring 17^a or otherwise in a short cylinder formed in one end of the main piston and the stem working in a cylinder in the interior of the emergency-valve. A T-shaped passage 23, constituting an emergency release-passage, is formed in this head and stem, one end of the passage terminating on the side of the stem and opening against the inner face of the emergency-valve, being closed 80 by the same except during emergency action. The other ends of the passage communicate with the train-pipe side of the chamber 3.

Operating in a cylinder in the cap 4 across the passage 11 is a release-controlling tube 85 24, having openings 25 therethrough, forming a continuous passage with passage 11, except in emergency action. This tube also has an opening or port 26, leading into chamber 3. The passage 11 is preferably of larger 90 dimensions than passage 26, whereby a quicker reduction of pressure is produced in chamber 2 than is produced in chamber 3. Consequently the release-piston 5 moves in advance of the main piston 17.

The slide-valve 6 is provided with a recess 27, which in release position connects the passage 28, leading from the brake-cylinder, with the passage 29, leading to the atmosphere, thereby forming the release mechanism of the device.

The air being admitted from the train-pipe into connection 10 enters passage 11 and passes through the passages in the release-

controller. The air then enters chamber 2, forcing the parts to the normal position shown in Fig. 1, and passes the piston 5, through the by-port, into the auxiliary reservoir. The air passes through the port 26 and enters the outer portion of the chamber 3, forcing the mechanism therein to the normal position shown in Fig. 1. When the air has entered the auxiliary reservoir, it will pass through passage 12 and enter the inner side of the chamber 3. Thence the air will pass through passages 30 in the main piston and enter the interior of the emergency-valve.

- Upon reduction of train-pipe pressure for service action the release-piston will move to the position shown in Fig. 2, closing the release from the brake-cylinder. The main piston will move outward, lifting the service-valve from the seat, whereupon the air from the auxiliary reservoir will flow through passages 12 and 30 and through the longitudinal grooves 31, formed on the stem of the service-valve, and enter the brake-cylinder through passage 14. In this action the emergency-valve remains seated, and only those parts concerned in service-work are brought into operation. Upon restoration of train-pipe pressure the parts return to their normal or running position and the brakes are released.
- Upon a reduction of train-pipe pressure for emergency action the release-piston moves as before, and the main piston will move sufficiently, so that the shoulder 21 abuts the ring 22 on the emergency-valve. The movement will bring the collar 32 on the stem of the service-valve into the restricted opening in the end of the emergency-valve, cutting off the flow of the auxiliary-reservoir air through the service-valve port. This movement will also open the inner end of the emergency release-passage 23, the head of the service-valve closing the passage 26, and the air on the outer side of the main piston in chamber 3 will flow through the release-passage 23 and the grooves 31 into the brake-cylinder, whereupon the excess of pressure in the inner portion of the chamber 3 will cause the main piston to make its full travel, as shown in Fig. 3, lifting the emergency-valve from the seat and uncovering emergency-port 15. The train-pipe pressure lifting the valve 16 will be admitted direct to the brake-cylinder, and the reservoir-air will also flow direct thereto through passage 14.
- Upon accumulation of pressure in the brake-cylinder in excess of that in the train-pipe the valve 16 will seat and cut off further direct communication between the train-pipe and brake-cylinder.
- The passage 11 as it enters the release-controller chamber is flared or extended inward to form a direct communication with the outer portion of chamber 3 and past the reduced portion of the release-controller tube E. At this time this tube interrupts communication of the passage 11 with the release-piston chamber X, whereupon in a restora-

tion of train-pipe pressure the air will first enter chamber 3 and force the parts therein to their normal position before passing into the chamber 2 to release the brakes.

At the lower side of the casing I prefer to form a drain device comprising a cup or chamber 33, provided with a removable screw-plug 34. This cup communicates with the chamber 3 by a passage 35, so that all condensed water will be drained from the valve device and be collected by the cup.

Although I have described more or less precise forms and details of construction, I do not intend to be understood as limiting myself thereto, as I contemplate changes in form, proportion of parts, and the substitution of equivalents as circumstances may suggest or render expedient without departing from the spirit and scope of my invention.

I claim—

1. In a device for actuating fluid-pressure brakes, the combination of a casing having a single passage for the admission of auxiliary-reservoir air and train-pipe air to a brake-cylinder, means for releasing the brake-cylinder and an emergency-valve and a service-valve separate from each other and controlling such passage, such valves being independent of the brake-release.

2. In a device for actuating fluid-pressure brakes, the combination of a casing having a chamber in communication with a brake-cylinder through a single passage, means for releasing the brake-cylinder and an emergency and service valve therein for controlling such passage for the admission of auxiliary-reservoir air and train-pipe air to the brake-cylinder, one of such valves operating within the other, and both valves being independent of the brake-release.

3. In a device for actuating fluid-pressure brakes, the combination of a casing having a chamber with ports in communication with an auxiliary reservoir, brake-cylinder and train-pipe respectively, two valves seated upon and controlling the port to the brake-cylinder, and brake-release mechanism separate and independent of the said valves.

4. In a device for actuating fluid-pressure brakes, the combination of a casing having two chambers, a slide-valve working in one of such chambers for controlling the brake-release, means for actuating the slide-valve, a single passage leading from the second chamber to a brake-cylinder for the passage of auxiliary-reservoir air in service action and of both auxiliary-reservoir air and train-pipe air in emergency action, a service-valve governing such single passage in service action, and an emergency-valve governing the same in emergency action and admitting both auxiliary-reservoir pressure and train-pipe pressure to the brake-cylinder.

5. In a device for actuating fluid-pressure brakes, the combination of a casing having two chambers, a slide-valve working in one of such chambers for controlling the brake-

release, a piston for operating the slide-valve, and a piston-actuated service and an emergency valve working in the other chamber but independent of each other, said valves being located on the same side of their piston.

6. In a device for actuating fluid-pressure brakes, a valve for admitting auxiliary-reservoir air to a brake-cylinder in service action only, acting in combination with a valve for admitting both train-pipe air and auxiliary-reservoir air to the brake-cylinder in emergency action, and brake-release mechanism separate and independent of said valves.

7. In a device for actuating fluid-pressure brakes, the combination of a release-valve for controlling the release of a brake-cylinder and feeding an auxiliary reservoir, a service-valve separate and independent of the release-valve, and an emergency-valve independent in operation from the other two valves.

8. In a device for actuating fluid-pressure brakes, the combination of a casing having two chambers, a release-valve working alone in one of such chambers and governing the brake-release, and for controlling the feed to the auxiliary reservoir and a service and an emergency valve working together in the other chamber but independent of each other.

9. In a device for actuating fluid-pressure brakes, the combination of a casing having two chambers, a brake-cylinder release-valve working in one of such chambers, and a service and an emergency valve working together in the other chamber, the latter chamber having communication with a brake-cylinder, auxiliary reservoir, and with a train-pipe through two ports, one a supply port or passage and the other an emergency-passage, the service-valve admitting reservoir-pressure to the brake-cylinder in service action and the emergency-valve admitting both reservoir-pressure and train-pipe pressure to the brake-cylinder in emergency action, the brake-release valve being independent of the other valves.

10. In a device for actuating fluid-pressure brakes, the combination of a piston-actuated slide-valve for controlling the brake-release and for controlling the feed to the auxiliary reservoir and piston-actuated valves for controlling the fluid-pressure in service and emergency action and independent of the brake-release.

11. In a device for actuating fluid-pressure brakes, the combination of a casing having two chambers, a piston-actuated valve in one of the chambers for controlling the brake-release and for controlling the feed to the auxiliary reservoir and a piston-actuated service-valve in the other chamber controlling the admission of auxiliary-reservoir air to a brake-cylinder, the service-valve being separate and independent in action from the brake-release.

12. In a device for actuating fluid-pressure brakes, the combination of a casing having two chambers, a slide-valve and its actuating mechanism located in one of such chambers for controlling the brake-release and for feeding the auxiliary reservoir, and valve mechanism operating in the other chamber to control the admission of air to a brake-cylinder in emergency and service applications of the brakes, such valve mechanism being separate and independent from the brake-release mechanism.

13. In a device for actuating fluid-pressure brakes, the combination of a slide-valve controlling communication between a brake-cylinder and the atmosphere, a piston operating the slide-valve and controlling communication between a train-pipe and an auxiliary reservoir and a valve controlling admission of air from the auxiliary reservoir to the brake-cylinder, the latter being separate and independent in action from the slide-valve.

14. In a device for actuating fluid piston-brakes, the combination of brake-release mechanism, a chamber having communication with a train-pipe, auxiliary reservoir and brake-cylinder, a piston traveling in such chamber, an emergency-valve within the piston and actuated by it, and a service-valve movable within the emergency-valve and actuated by the piston.

15. In a device for actuating fluid-pressure brakes, the combination of a casing having two chambers, mechanism located in one of the chambers for releasing the brakes and feeding up an auxiliary reservoir, the other chamber having ports communicating with an auxiliary reservoir, a brake-cylinder and a train-pipe respectively, a piston operating in such second chamber and having a central bore or opening and two independent valves concentrically arranged within the bore of the piston and controlling the port to the brake-cylinder.

16. In a device for actuating fluid-pressure brakes, the combination of a casing having a chamber in communication with an auxiliary reservoir, train-pipe and brake-cylinder respectively, and an emergency and a service valve separate from each other but acting together to close the passage to the brake-cylinder, means for operating the valves, brake-cylinder-release mechanism separate and independent of the valves and their said operating means.

17. In a device for actuating fluid-pressure brakes, the combination of a casing having two chambers, the first chamber being in communication respectively with a train-pipe and auxiliary reservoir, a piston traveling in such first chamber, means of feeding the auxiliary reservoir, a slide-valve actuated by the piston for controlling the brake-release, and an emergency-valve and a service-valve in the second chamber for controlling a passage to the brake-cylinder from such second chamber.

18. In a device for actuating fluid-pressure brakes, the combination of a chamber having a port or passage to a brake-cylinder, a valve seated upon such port and closing a portion thereof and a second valve having its end

seated upon the first valve and closing that portion of the port left open by the first valve.

19. In a device for actuating fluid-pressure brakes, the combination of a casing having a 5 chamber provided with ports communicating with an auxiliary reservoir, brake-cylinder and train-pipe respectively, a valve having a hole or opening through its end and seated upon the port to the brake-cylinder to close 10 the same except for such opening and a second valve movable within the first valve and having its end normally seated upon the opening through the same to close it.

20. In a device for actuating fluid-pressure 15 brakes, the combination of a casing having a chamber therein with ports communicating with a train - pipe, auxiliary reservoir and brake-cylinder respectively, a piston traveling in the chamber, a service and an emergency valve together fully closing the port to the brake-cylinder and actuated by the piston, and independent mechanism for releasing the brakes and feeding the auxiliary reservoir.

21. In a device for actuating fluid-pressure 25 brakes, the combination of a casing having a chamber therein with ports communicating with a train - pipe, auxiliary reservoir and brake-cylinder respectively, a piston in the 30 chamber, a service and an emergency valve separate from each other and adapted together to fully close the port to the brake-cylinder, the piston actuating the service-valve to partially open the port to the brake-cylinder upon a reduction of pressure for 35 service action and actuating the emergency-valve to fully open the port to the brake-cylinder upon a reduction of pressure for emergency action, and brake-release mechanism 40 independent of such valves.

22. In a device for actuating fluid-pressure 45 brakes, the combination of a casing having a chamber therein with ports communicating with a train - pipe, auxiliary reservoir and brake-cylinder respectively, a piston traveling in the chamber and closing the train-pipe port except in emergency action, and a valve 50 actuated by the piston to govern the brake-cylinder port from such chamber, and means for releasing the brake-cylinder.

23. In a device for actuating fluid-pressure 55 brakes, the combination of a casing having a chamber therein, a piston in the chamber, a train-pipe port entering the chamber behind the piston, an emergency passage or port from the train-pipe and entering the chamber but closed by the piston except in emergency action when it opens in front of the piston, a port or passage from the auxiliary reservoir, 60 a port or passage from the chamber to the brake-cylinder, both latter ports being located in the chamber in front of the piston, and two lift-valves actuated by the piston and together closing the brake-cylinder port, a service reduction of train-pipe pressure causing 65 one of the valves to lift to partially open the brake-cylinder port to admit auxiliary-reser-

voir pressure to the brake-cylinder, and an emergency reduction of train-pipe pressure causing the piston to open the emergency- 7 passage and causing the other valve to lift to fully open the brake-cylinder port and admit auxiliary-reservoir air and train-pipe air to the brake-cylinder.

24. In a device for actuating fluid-pressure 7 brakes, a casing having a brake-cylinder release-valve chamber and an operating-valve chamber service action mechanism in such latter chamber in combination with means for producing a greater reduction of train-pipe pressure in the release-valve chamber than in the operating-valve chamber in setting the brakes.

25. In a device for actuating fluid-pressure 8 brakes, a brake-cylinder release-valve chamber and an operating-valve chamber in combination with means for producing a greater reduction of pressure in the release-valve chamber than in the operating-valve chamber in setting the brakes, and for producing 9 a greater train-pipe pressure in the operating-valve chamber than in the release-valve chamber upon a restoration of train - pipe pressure.

26. In a device for actuating fluid-pressure 9 brakes, the combination of a casing having two chambers both normally in communication with a train-pipe, a brake-release device in one of the chambers, valve mechanism in the other chamber for controlling the admission of air to a brake-cylinder and means for cutting off the supply of train-pipe air to the brake-release chamber.

27. In a device for actuating fluid-pressure 10 brakes, the combination of a casing having two chambers, a brake-cylinder-release device in one chamber and valve mechanism in the other chamber for admitting fluid-pressure to a brake-cylinder, a supply pipe or 11 passage from the train-pipe and communicating with the chambers respectively and a valve device movable across the passage for cutting off the supply to the release-chamber.

28. In a device for actuating fluid-pressure 11 brakes, the combination of a casing having a chamber, a piston therein, a valve mechanism actuated by the piston for admitting fluid-pressure to a brake-cylinder from both the auxiliary reservoir and train - pipe and an emergency release-passage for releasing the fluid-pressure behind the piston and into the brake-cylinder in emergency action only.

29. In a device for actuating fluid-pressure 11 brakes, the combination of a casing having a chamber, a piston therein with auxiliary-reservoir air on one side and train-pipe air on the other, a service-valve operated by the piston and movable therein, such valve controlling the admission of auxiliary-reservoir air to the brake-cylinder in service action and having a normally-closed passage for venting the train-pipe air from the chamber behind the piston and into the brake-cylinder in emergency action.

30. In a device for actuating fluid-pressure brakes, the combination of a casing having a single passage for the admission of fluid-pressure to a brake-cylinder and an emergency-valve and a service-valve acting together in running position to close such passage with their combined ends, the service-valve being adapted to lift to partially open the passage in service action and forming direct communication from the auxiliary reservoir to the brake-cylinder, and the emergency-valve opening the passage fully in emergency action.

31. In a device for actuating fluid-pressure brakes, the combination of a casing having a

chamber with an always-open passage from an auxiliary reservoir and with a normally-closed passage therefrom to a brake-cylinder and mechanism in such chamber adapted to open the brake-cylinder passage in the application of the brakes and for admitting train-pipe air into the chamber and thence into the brake-cylinder through said brake-cylinder passage in emergency action and independent brake-release mechanism. 20
